FURNITURE LEG

Robert E. Kjer Jakobsen, Manhattan Beach, Calif., assignor to Virtue Bros. Mfg. Co., Los Angeles, Calif., a corporation of California

Application December 5, 1955, Serial No. 39,160

Term of patent 14 years

(Cl. D33—14)

Fig. 1 is an elevational view of a furniture leg showing my new design.

Fig. 2 is an enlarged elevational view of the upper end of said leg.

Fig. 3 is a cross-sectional view as taken on line 3—3 of Fig. 2 and looking in the direction of the arrows.

Fig. 4 is an elevational view, to the scale of Fig. 2, of the lower end of the leg.

Fig. 5 is a cross-sectional view as taken on line 5—5 of Fig. 4 and looking in the direction of the arrows.

The dominant features of the design are shown in the drawing in full lines.

I claim:

The ornamental design for a furniture leg, substantially as shown and described.
